EXTENSIBLE HAY RACK

Filed Sept. 10, 1930

Karl Lichtenhager

INVENTOR:

BY *Victor J. Evans*

His ATTORNEY.

UNITED STATES PATENT OFFICE

KARL LICHTENTHALER, OF STAUNTON, ILLINOIS

EXTENSIBLE HAYRACK

Application filed September 10, 1930. Serial No. 481,000.

This invention relates to certain novel improvements in extensible hay racks, and has for its principal object the provision of an improved construction of this character which will be highly efficient in use and economical in manufacture.

Among the several objects of this invention is the provision of an improved construction of the character described herein which when not in use can be stored in a compact space such as under a small roof.

Other objects will appear hereinafter.

The invention consists in the novel combination and arrangement of parts to be hereinafter described and claimed.

The invention will be best understood by reference to the accompanying drawings, showing the preferred form of construction and in which:

20 Fig. 1 is a side elevational view depicting a preferred form of construction of my improved wagon box and hay rack;

Fig. 2 is a plan view of the invention as depicted in Fig. 1, taken substantially on the 25 line 2—2 in Fig. 1; and

Fig. 3 is a sectional view taken substantially on the line 3—3 in Fig. 2.

Referring to the drawing wherein a preferred form of construction of my invention is depicted, indicated at 10 is a front wheel bearing axle structure which may be of any approved type so as to support the front wheels 11 and 12. Extended between the front axle structure 10 and a suitable rear 35 wheel bearing axle structure 13 is an extensible reach 14 of any approved type known in the art. Carried by the rear axle structure 13 are the rear wheels 15 and 16. Associated with the front axle structure 10 is a 40 tongue 17 which may be of any approved type.

The tongue structure 17 is swivelly connected to the front axle structure 10 by means of the circle 18 as is well known in the 45 art. Carried by the front axle structure 10 is a cross piece 19 which may be of any approved type and in the present instance this portion 19 is similar to a cross piece 20 carried by the rear axle structure 13. The foregoing described structure constitutes no part

of my invention and may be of any approved type.

My improved hay rack construction includes a box-like structure generically indicated at 21. Mounted on the box 21 are angle irons 22 and 23 which are adapted to engage the cross piece 19 when my improved device is mounted in operative position and, as is well understood in the art, these portions 22 and 23 prevent longitudinal movement of the box 21 when the box is in operative position. Angle irons or the like 24 and 25 are carried by the box 21 in position so as to cooperate with the rear cross piece 20.

The side walls of my improved box 21 are defined by similar front and rear pairs of elongated channel irons 26 and 27. The front pair of irons 26 and 27 are secured together by end plates 28 and suitable securing elements such as 30 and 31. The rear pair of irons 26 and 27 are secured together by plates 29 and suitable connecting elements 31. As best shown in Fig. 3, these channel irons 26 and 27 are substantially rectangular in cross section to provide inwardly extending flanges 26' and 27' and are spaced apart at the middle of the box 21 as indicated at 90. Provided at spaced apart intervals in the longitudinal extent of the channel irons 26 and 27 are plates 32 and 33 which are secured to the channel irons 26 and 27 by means of suitable connecting elements 34. Extending longitudinally between the channel irons 26 and 27 are boards 44 which are extensible with 75 respect to the channel irons 26 and 27. The plates 32 and 33 are connected to the boards 44 by means of bolt and nut structures 35. Adjacent the middle of the box 21 and at the inner ends of the irons 26 and 27 I provide plates 36 and 37 which are rigidly secured to the channel irons 26 and 27 by means of suitable securing elements 38 and 39. The plates 36 are attached to the boards 44 by means of bolt and nut structures 40 and the plates 37 are attached to the boards 44 by means of suitable bolt and nut structures 41.

Extending between the channel irons 27 at the front end of the box 21 is an angle iron plate. A similar angle iron 45 is provided 100

at the rear of the box 21 and this iron 45 extends between the plates 29.

The bottom of the box 21 is provided by planks 47 which at the rear ends thereof are mounted upon and secured to the angle iron 45 by means of securing elements 46, while the front end portions of the planks 47 rest upon and are secured to the angle iron 42 by means of securing elements 48.

10. It is manifest, therefore, that the box 21 may be extended by removing the bolt and nut structures 35, 40, 41 and 36 from each of the side walls and then removing the bolts 43 and 46 from the floor planks 47. It is 15 apparent that I may thus provide planks 47 of various lengths corresponding to the various lengths to which the box 21 may be extended and to facilitate securing the bolts and nut structures 35, 40 and 41 in the several 20 positions to which the box 21 may be extended I provide suitable openings in the boards 28.

Mounted on the flange portions 26' of the rearwardly disposed pairs of channel irons 25 26 and at the rear thereof are standards 47 which include foot portions 27' which are attached to the flange portions 26' by means of suitable securing elements 48. Disposed forwardly of the standards 47 are similar standards 49 which include foot portions 49' which are attached to the flange portions 26' by means of securing elements 50. Disposed between the standards 47 and 49 and extending transversely of the box 21 is an angle iron 35 51 which includes a flange portion 51 and this angle iron 51 is secured to the standards 47 and 49 by means of securing elements 52.

Spaced forwardly of the standards 47 and 49 on the rearwardly disposed pair of irons 40 26 and 27 are similar standards 53 and 54 which are mounted on the flange portions in a manner similar to that described for the standards 47 and 49 and these standards support a transversely extending angle iron 55 45 which includes a flange portion 55'.

Mounted on the flange portions 51' and 55' and extending parallel to the side walls of the box 21, but spaced apart therefrom, as shown in Figs. 2 and 3, are boards 56. 56 These boards 56 are secured to the flange portions 51' and 55' by means of suitable bolt and nut structures 58 and 59.

Standards 60 are provided at the front end of the box 21 on the forward pair of irons 55 26 and 27 and these standards include foot portions 60' which are attached to the flanges 26' by means of securing elements 61. Adjacent the standards 60 are standards 62 which include foot portions 62' that are secured to the flange portions 26' by means of suitable securing elements and these standards 60 and 62 support a transversely extending channel iron 63 which is attached to the standards 60 and 62 by means of suitable 60 65 securing elements. Standards 65 and 66 sim-

ilar to the standards 60 and 62 are provided on the flange portions 26' of the forward pair of irons 26 and 27 and these standards support an angle iron 67 which is similar to the angle iron 63 and includes a flange portion 67'. Extending between the flange portions 67' at opposite sides of the box 21 are boards 68 which are extended parallel to the boards 56 but spaced below the boards 56 as shown in Figs. 1 and 3. The boards 68 are connected to the flange portions 67' and 68' by means of bolt and nut structures 69 and 70.

It may be seen, therefore, by referring to Fig. 1, that when the box 21 is extended in the manner described hereinbefore the 80 boards 68 will move slidably under the boards 56 so that my improved hay rack may be extended to any desired length.

My improved hay rack includes a ladder structure generically indicated at 71. The ladder 71 comprises spaced apart legs 72 and 73 to which are secured in any approved manner plates 74 and 75 and, as shown in Fig. 2, these plates 74 and 75 are mounted for swinging movement on a shaft 76 which carries spacing collars 77 and 78. The end portions 76' of the shaft 76 are mounted in any approved manner in suitable openings provided therefor in the plates 30. Extending between the legs 72 and 73 of the ladder 71 are the cross pieces 79.

It is apparent, therefore, that the ladder 71 may be moved forwardly into operative position, as shown in Figs. 1 and 2, and in this position the legs 72 and 73 of the ladder rest against the angle iron 42 while when not in use the ladder 71 may be disposed on the floor of the box 21.

At the rear of my improved hay rack I provide standards 80 and 81, for purposes well understood in the art. The standards 80 and 81 are provided by arms 82 and 83 which are secured respectively to plates 84 and 85 by means of securing elements 86 and 87. The plates 86 and 87 include similar offset portions 84' and 85' and these offset portions are mounted for swinging movement in the plates 29 by means of bolts 88 and 89. The standards 80 and 81 when in operative position rest on the floor planks 47.

From the foregoing description of my invention it is manifest that I have provided an improved hay rack construction which may be extended to various lengths and which, when not in use, may be stored in a compact space. It is likewise apparent from the foregoing description of my invention that while being simple and economical in construction my invention is highly convenient and efficient in use.

While I have illustrated and described the preferred form of construction for carrying my invention into effect, this is capable of variation and modification, without departing from the spirit of the invention. I,

therefore, do not wish to be limited to the precise details of construction set forth, but desire to avail myself of such variations and modifications as come within the scope of the appended claims.

Having thus described my invention what I claim as new desire to protect by Letters Patent is:

1. An extensible hay rack comprising a box-like structure having an open upper side, the side walls of said structure comprising co-operating front and rear pairs of spaced apart substantially L-shaped members defining longitudinally extending slots therebetween, elongated members mounted for slidable movement in said slots, means for supporting said slidable members between said L-shaped members and in said slots, upright members carried by said L-shaped members, members carried by said upright members and extending transversely of said box-like structure, and longitudinally extending members carried by said transversely extending members and extensible with said box-like structure.

2. An extensible hay rack comprising a box-like structure having an open upper side, the side walls of said structure comprising co-operating front and rear pairs of spaced apart substantially L-shaped members defining longitudinally extending slots therebetween, elongated members mounted for slidable movement in said slots, means for supporting said slidable members between said L-shaped members and in said slots, upright members carried by said L-shaped members, members carried by said upright members and extending transversely of said box-like structure, and longitudinally extending members carried by said transversely extending members and extensible with said box-like structure, said last mentioned members being spaced apart from the side walls of said box-like structure.

3. An extensible hay rack comprising a box-like structure having an open upper side, the side walls of said structure comprising co-operating front and rear pairs of spaced apart substantially L-shaped members defining longitudinally extending slots therebetween, elongated members mounted for slidable movement in said slots, means for supporting said slidable members between said L-shaped members and in said slots, upright members carried by the front pair of said L-shaped members, other upright members carried by the rear pairs of said L-shaped members, supporting members carried by said upright members and extending transversely of said box-like structure, longitudinally extending members carried by said first named supporting members, said last-mentioned members being spaced apart from the side walls of said box-like structure, other longitudinally extending members carried by said second named upright members, spaced apart from

the side walls of said box-like structure, and including portions adapted to have sliding engagement with said first-named longitudinally extending members.

4. An extensible hay rack comprising a box-like structure having an open upper side, the side walls of said structure comprising co-operating front and rear pairs of spaced apart substantially L-shaped members defining longitudinally extending slots therebetween, elongated members mounted for slidable movement in said slots, means for supporting said slidable members between said L-shaped members and in said slots, upright members carried by the front pairs of said L-shaped members, other upright members carried by the rear pairs of said L-shaped members and relatively higher than said first-named upright members, supporting members carried by said first-named upright members and extending transversely of said box-like structure, supporting members carried by said second-named upright members, longitudinally extending members carried by said first-named supporting members, spaced apart from, and extending parallel to the side walls of said box-like structure, and other longitudinally extending members carried by said second-named supporting members, spaced apart from, and extending parallel to the side walls of said box-like structure, said last-mentioned members including portions adapted to be slidable over portions of said first-named longitudinally extending members whereby said longitudinally extending members may be extended with said box-like structure.

In testimony whereof I affix my signature.
KARL LICHTENTHALER.
